UNITED STATES PATENT OFFICE.

EDWARD A. J. LEAHY, OF NEW YORK, N. Y., ASSIGNOR TO REGAL HOOF PAD COMPANY, OF NEW YORK, N. Y., A CORPORATION OF NEW YORK.

DESIGN FOR A HOOF-PAD.

41,330.

Specification for Design.

Patented Apr. 25, 1911.

Application filed December 14, 1909. Serial No. 533,125. Term of patent 14 years.

To all whom it may concern:

Be it known that I, EDWARD A. J. LEAHY, a citizen of the United States, residing at New York, in the county of New York and State of New York, have invented a new, original, and ornamental Design for Hoof-Pads, of which the following is a specification, reference being had to the accompanying drawings, forming a part thereof.

Figure 1 is a plan view of a hoof pad con-

structed in accordance with my design; and Fig. 2 is a side elevation of the same.

I claim:

The ornamental design for a hoof pad as shown.

EDWARD A. J. LEAHY.
